(57) **CLAIM**

The ornamental design for precision screwdriver as shown and described.

DESCRIPTION

1. Precision screwdriver

1.1 : Perspective

1.2 : Perspective

1.3 : Front

1.4 : Back

1.5 : Left

1.6 : Right

1.7 : Top

1.8 : Bottom

1.9 : Enlarged

The broken lines shown in the drawings represent portions of the precision screwdriver that form no part of the claimed design; Fig. 1.1 is a front, right and top side perspective view of a precision screwdriver showing our new design; Fig. 1.2 is a rear, left and bottom side perspective view thereof; Fig. 1.3 is a front elevation view thereof; Fig. 1.4 is a rear elevation view thereof; Fig. 1.5 is a left side elevation view thereof; Fig. 1.6 is a right side elevation view thereof; Fig.

(Continued)

1.7 is a top plan view thereof; Fig. 1.8 is a bottom plan view thereof; and Fig. 1.9 is an enlarged view of the portion marked '9' of Fig. 1.1.
